CLAIM

I claim the ornamental design for an electrical connector, as shown.

DESCRIPTION

FIG. 1 is a perspective view of an ornamental design of an electrical connector according to my invention;

FIG. 2 is a rear perspective view thereof;

FIG. 3 is a front view thereof;

FIG. 4 is a right side view thereof;

FIG. 5 is a left side view thereof;

FIG. 6 is a rear view thereof;

FIG. 7 is a top view thereof;

FIG. 8 is a bottom view thereof;

FIG. 9 shows a perspective view of the electrical connector showing its environment wherein it is coupled to a cable connector; and,

FIGS. 10, 11 and 12 are front views of alternate embodiments of the invention, the remaining views thereof are identical to those of the embodiment of FIGS. 1-9 except for the positions of the side and top grooves.
